CARBIDE LAMP

Charles W. Schafer, Galena, Kans.

Application August 24, 1936, Serial No. 97,694

1 Claim. (Cl. 48—4)

The invention relates to a lamp of the acetylene type which is adapted to be used by miners but may be otherwise serviceable.

The primary object of the invention is the provision of a lamp of this character, wherein a sponge body, preferably made from soft rubber so that it will be porous, is placed about the water feed tube of such lamp for the purpose of preventing sudden flow of water, particularly when 10 the lamp is in action on the head gear of a wearer with the lamp in an upright position and such wearer suddenly stoops over to bring it slightly below horizontal position which necessarily would cause the flooding of the burner tip and resultant 15 extinguishing of the light.

Another object of the invention is the provision of a lamp of this character, wherein the porous body or pad fitted within the same will function as a filter to avoid choking or stopping up of the 20 burner tip and retarding the flooding of the said tip by water with the result that the flame will be constant when the lamp is lighted and at the same time the corroding of the threads joining the carbide holder with the water font will be 25 prevented and in this manner maintaining the lamp in a working condition.

A further object of the invention is the provision of a lamp of this character, wherein the porous disk fitted within the same will serve to 30 clean the gas and also maintain the burner tip free from particles of carbide and at the same time assure a more constant pressure at the burner tip resulting in the uniform flame.

A further object of the invention is the provision of a lamp of this character, which is simple in construction, thoroughly reliable and efficient in its operation, self-cleaning, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and 45 pointed out in the claim hereunto appended.

In the accompanying drawing:

Figure 1 is a vertical longitudinal sectional view through a lamp constructed in accordance with the invention.

50 Figure 2 is a sectional view on the line 2—2 of Figure 1 looking in the direction of the arrows.

Figure 3 is a side elevation of the porous pad for fitting within the lamp and removed therefrom.

55 Similar reference characters indicate corre-

sponding parts throughout the several views in the drawing.

Referring to the drawing in detail, the lamp, which is of conventional form, includes a carbide holder 10, a water font 11 and a burner 12, respectively. Leading from the font 11 into the carbide holder is a water feed tube 13 which is centrally located relative thereto and is equipped with a hand operated valve 14 for regulating the feed of water from the font to said carbide 10 holder 10.

The bottom 15 of the font 11 serves as a cover or top for the carbide holder 10 and opening through this bottom is the inner end of the burner 12, it having a burner tip 16 at its outer end. The 15 acetylene gas formed within the holder 10 passes into the burner 12 and is lighted at the tip 16 as is usual. The feed of water from the font 11 to the carbide holder 10 is regulated and controlled by the valve 14 in the ordinary well-known 20 manner.

Surrounding the tube 13 beneath the bottom 15 of the font 11 is a sponge rubber pad 17 of disk form and is carried upon a solid rubber sleeve 18 snugly embracing the tube 13. This sleeve 18 25 has its lower end extended beyond the pad 17 and is of enlarged annular formation providing a circular rim or flange 19 having a sloping surface 20. The pad 17 at its under face is convexed or downwardly tapered at 21 and such face for 30 substantially one half of the diameter of said pad carries an impervious facing of solid rubber coating 22 which is located on the application of the pad 17 to the tube 13 and within the lamp is directed beneath the port 23 establishing communication between the carbide container 10 and the burner 12, this port 23 being in the bottom 15 of the font 11 so that acetylene gas formed within the container 10 will percolate through the uncoated or surfaced area of the pad 17 and find 35 its way through this pad into the burner 12. In this manner the gas is filtered so that when pressure is created within the container 10 small particles of carbide or other foreign matter will be prevented from passing into the burner 12 and 40 clogging or choking the tip 16 thereof. The pad 17 also functions to maintain a constant flame 45 at the tip 16 when lighted in that the pressure within the container 10 for the carbide will be uniform in the functioning of such pad.

The flange 19 on the sleeve 18 carrying the pad 17 will avoid water deposits on the tube 13 working upwardly thereof from within the carbide holder 10 and any accumulation of water on the pad 17 at the under face thereof will have flow 50 55

therefrom over the surface 20 of the flange 19 for dropping back into the carbide holder 10.

The pad 17 when within the lamp will serve to seal the joint between the container 10 and the font 11 to avoid corroding of the threaded connections 24 therebetween and at the same time sealing the joint at the said threaded connections 24 to avoid leakage of acetylene gas from the container 10 when the latter is fitted with the font 11.

The pad 17 is porous excepting at the coating or facing 22 while the sleeve 18 is non-porous and the latter frictionally holds the said pad 17 in place upon the water tube 13 when such sleeve 15 is fitted thereon.

What is claimed is:

A filtering pad for a carbide lamp having a

carbide container, a water font separably connected with said container and a feed water tube leading from the font to said container comprising a spongy porous body having an opening receiving said tube and fitted in the separable joint between the container and font for the sealing of said joint, a solid rubber sleeve fitting the opening in the said body and snugly embracing the tube, the said sleeve being extended below the body and having an enlarged annular formation providing a circular rim with a sloping upper face beneath said body, the body at its under face being downwardly tapered, and an impervious facing over substantially one-half of the diameter of the said downwardly tapered under face of the body.

CHARLES W. SCHAFER.
